UNITED STATES PATENT OFFICE.

CHARLES W. CUDDON, OF NEW KENSINGTON, PENNSYLVANIA, ASSIGNOR
TO THE BROWNSVILLE PLATE GLASS COMPANY, OF SAME PLACE.

DESIGN FOR SHEET-GLASS.

SPECIFICATION forming part of Design No. 23,467, dated July 17, 1894.

Application filed June 21, 1894. Serial No. 515,313. Term of patent 7 years.

To all whom it may concern:

Be it known that I, CHARLES W. CUDDON, a citizen of the United States, residing at New Kensington, in the county of Westmoreland 5 and State of Pennsylvania, have invented or discovered a new Design for Sheet-Glass, of which the following is a specification.

In the accompanying drawings which make part of this specification, Figure 1 is a plan 10 view of my design; Fig. 2, a section of same.

The design consists essentially of plumes grouped so as to cover thickly the surface of the glass. These plumes are so bent and arranged that they form substantially a unit 15 square, which may indefinitely be repeated, until a sheet of glass of any desired size is closely decorated.

In order to give a uniform brilliancy to decorated sheet glass, it is necessary that the 20 interstices between the portions of the pat-

tern, be as few and small as possible. For this reason the plumes are turned in various directions, coiled or made straight, and certain of the plumes have vanes only on one side of the quill.

The vanes themselves are in raised relief and to secure the most brilliant effects the height of a vane should be about half of the width of the base. It is essential that the height of the vane should be from a thirty- 25 second to a sixteenth of an inch.

Having described my invention, I claim—

The design for sheet glass, substantially as herein shown and described.

In testimony whereof I have hereunto set 35 my hand this 11th day of June, A. D. 1894.

CHARLES W. CUDDON.
